UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,277,386.

Specification of Letters Patent.

Patented Sept. 3, 1918.

Application filed January 2, 1918. Serial No. 209,973.

To all whom it may concern:

Be it known that I, HENRY P. CLAUSEN, a citizen of the United States, residing at Mount Vernon, in the county of West-
chester, State of New York, have invented certain new and useful Improvements in Telephone-Exchange Systems, of which the following is a full, clear, concise, and exact description.

10 This invention relates to telephone exchange systems and more particularly to such systems of the central energy type in which signaling current is automatically connected with a called-for telephone line.

15 An object of this invention is the provision of a system of this character employing improved means for controlling the application of signaling current to the line.

In accordance with this invention, a link 20 circuit employed in connecting together telephone lines is equipped with apparatus under the joint control of a listening key and the connection of the link circuit with a called-for telephone line for connecting 25 therewith a source of signaling current. The link circuit is also equipped with apparatus controlled by a connected calling telephone line, whereby when a recall is made from the calling line, signaling current 30 rent is automatically disconnected from the called-for line.

This invention will be more fully understood from the following description considered in connection with the accompanying drawing, illustrating one embodiment thereof.

In the drawing there are shown two telephone lines, A and B, terminating at a central office, at which is located a cord circuit C for interconnecting the line for conversation. It will be understood that many lines similar to lines A and B and a plurality of cord circuits similar to the cord circuit C, may be and are in practice usually 40 provided, but, for convenience, only the two lines and the one cord circuit are shown. It is thought that the present invention will be best understood from the description of the operation of the system disclosed in the 45 drawing and it will be so described.

Subscriber A in initiating a call removes the receiver from the switchhook, causing the energization of line relay 5 and the lighting of line lamp 6. The operator observing the lighted condition of the lamp

6, inserts calling plug 7 of the cord circuit C into line jack 8 of the calling line A. Relay 9 and cut-off relay 10 thereupon operate. The operation of cut-off relay 10 disconnects the line relay 5 from the line, thereby 60 extinguishing the lamp 6. Relay 9 in operating closes the circuit of answering supervisory lamp 11, but the lamp is not lighted, for as soon as the plug 7 is inserted in the jack 8, supervisory relay 12 is operated over 65 the line, thereby opening the circuit of the lamp 11. However, since the contact of relay 9 is made before the normal contact of supervisory relay 12 is opened, relay 15 is operated over a circuit from battery 70 through the lower normal contact of listening key 16, the left-hand normal contact of the relay 15, the normal contact of supervisory relay 12, and the contact of relay 9 to ground. Relay 15, in operating, connects an interrupter 17 through its right-hand alternate contact to the alternate contact of supervisory relay 12, so that upon the energization of the supervisory relay 12, the lamp 11 is intermittently lighted to 80 furnish to the operator a signal indicating that some act upon her part is required.

Relay 15, in operating, also establishes a locking circuit for itself through its left-hand normal contact and the contact of relay 9, thereby removing relay 15 from the control of the supervisory relay 12. The energization and locking up of relay 15 as described, presupposes that the listening key 16 is in its normal position when the 90 plug 7 is inserted in the jack 8. If this key had been in its actuated condition, relay 15 would not then be operated. The actuation of the listening key connects the operator's telephone set 18 with the talking 95 strands of the cord circuit and opens the locking circuit of relay 15 which releases, stopping the intermittent lighting of the answering supervisory lamp 11.

Upon being advised that the calling subscriber A desires to be connected with the line of subscriber B, the operator tests the called-for line (it being assumed that all of the lines are provided with multiple jacks) to determine the idle or busy condition of the line. Assuming the line to be idle, the calling plug 25 is inserted into line jack 26 and the listening key 16 is restored to normal position. Relay 27 and cut-off relay 28 are operated upon the in- 110

sertion of the plug 25 into the jack 26. Relay 27, in operating, causes the lighting of calling supervisory lamp 24. The operation of relay 27 and the restoration of 5 the listening key 16 to its normal position, connects ringing current to line B over a circuit from a source of ringing current 29 through the upper normal contact of listening key 16, right-hand normal contact of 10 relay 15, winding of trip relay 30, right-hand alternate contact of relay 27, upper normal contact of relay 31, tip contacts of the plug 25 and the jack 26, right-hand alternate contact of cut-off relay 28, out 15 over one side of line B, through the call bell 32 and condenser 33, back over the other side of the line, left-hand alternate contact of cut-off relay 28, ring contacts of the jack 26 and the plug 25, middle normal contact of relay 31, resistance 34, and 20 battery to ground. The path by way of the resistance 34 is provided in shunt of the relay 27, so that there will be no tendency for the relay 27 to chatter while ringing current is connected with the line. 25

Subscriber B, in responding to the operation of the call bell 32, removes the receiver from its switchhook, thereby causing the operation of trip relay 30, removing 30 a short circuit from the winding of relay 31. Relay 31 thereupon operates over a circuit from battery through the winding of relay 31, resistance 35 and left-hand contact of relay 27 to ground.

35 Relay 31, in operating, opens another contact in the short circuit about its own winding, so that this short circuit cannot be reestablished when trip relay 30 releases its armature upon the opening of the upper normal contact of relay 31. Relay 31, in closing its alternate contact completes a circuit for supervisory relay 36, and in opening its middle normal contact removes the resistance 34 from shunt relation to the 40 winding of relay 27. The talking circuit having been completed, the calling supervisory relay 36 is energized to extinguish 45 the calling supervisory lamp 24.

At the conclusion of the conversation, the 50 subscribers restore the receivers to the switchhooks, the restoration of subscriber B's receiver to the switchhook causing the release of supervisory relay 36 and the lighting of the supervisory lamp 24 to furnish 55 a disconnect signal. The restoration of the receiver to the switchhook by subscriber

A, causes the release of supervisory relay 12 and the lighting of supervisory lamp 11 to furnish a disconnect signal. Relay 15 60 is also operated over the circuit hereinbefore described, and locks up. The operator may now withdraw the plugs from the jacks, whereupon all apparatus is restored to its normal condition.

65 If, after the calling plug has been in-

serted in the line jack 26 and the ringing current is connected to line B, the calling subscriber A restores the receiver to the switchhook, the release of supervisory relay 12 causes the energization and locking up 70 of relay 15 as already described. Relay 15, in operating, opens its right-hand normal contact which is included in the path of ringing current, thereby disconnecting ringing current from the called line. In 75 this manner, whenever the calling subscriber restores the receiver to the switchhook after ringing current has been connected with the called line, the ringing current is automatically disconnected therefrom. Should 80 the calling subscriber, after having restored the receiver to the switchhook, immediately remove it therefrom to make a recall, this subsequent removal of the receiver from the switchhook before the plug 7 is withdrawn 85 from the jack 8, causes the energization of the supervisory relay 12, whereupon the interrupter 17 is included in circuit with the answering supervisory lamp 11. This supervisory lamp is thereby intermittently 90 lighted to furnish a recall signal. The operator, observing such intermittent operation of the lamp 11, may actuate listening key 16 to connect the operator's telephone set to the talking strands of the cord circuit. The actuation of the listening key 95 16 opens a contact in the locking circuit of relay 15, which thereupon releases its armatures, disconnecting the interrupter from circuit relation with the lamp 11. 100

While the relay 15, in releasing its armatures, again closes its right-hand normal contact which is in the path of ringing current, ringing current is not thereby reconnected to the called-for line, because this 105 path for ringing current also includes the upper normal contact of listening key 16, which is open since the key is now actuated.

What is claimed is:

1. A telephone exchange system comprising a telephone line, a link circuit, an operator's telephone set, a listening switch controlling the connection and disconnection of the operator's telephone set to and from the link circuit, electromagnetic switching means responsive to the connection of the link circuit with the telephone line, and a source of signaling current connected with the telephone line through contacts of the listening switch and the electromagnetic switching 110 means.

2. A telephone exchange system comprising a telephone line, a link circuit, an operator's telephone set, a listening switch controlling the connection and disconnection of the operator's telephone set to and from the link circuit, a relay energized upon the connection of the link circuit with the telephone line, a source of signaling current, and circuit connections therefor including a con- 115 120 125 130

tact of the listening switch and an engaged contact of the energized relay for connecting the source of signaling current with the telephone line.

- 5 3. A telephone exchange system comprising a calling and a called telephone line, a link circuit connected with the calling telephone line, a relay in the link circuit controlled from the calling telephone line, an 45
 10 operator's telephone set, a listening switch controlling the connection and disconnection of the operator's telephone set to and from the link circuit, a relay energized upon the connection of the link circuit with the called line, a source of signaling current, and the circuit connections therefor including a contact of the listening switch, a contact of the relay controlled from the calling line, and engaged contacts of the energized relay for 50
 15 connecting the source of signaling current with the called telephone line.

4. A telephone exchange system comprising a calling and a called telephone line, a link circuit connected with the calling line, a 55
 20 operator's telephone set, a listening switch controlling the connection and disconnection of the operator's telephone set to and from the link circuit, a relay in the link circuit controlled from the calling line and by the listening switch, a relay energized upon the connection of the link circuit with the called line, and a source of signaling current connected with the called line through engaged contacts of the energized relay when the listening switch and the first mentioned relay are in their normal positions. 60
 25
 30
 35

5. A telephone exchange system comprising a calling and a called telephone line, a link circuit connected with the calling line, 65
 40

an operator's telephone set, a listening switch controlling the connection and disconnection of the operator's telephone set to and from the link circuit, a relay in the link circuit controlled from the calling line 45 and by the listening switch, and a source of signaling current connected with the called line through normally closed contacts of the relay and the listening switch when the link circuit is connected with the called 50 line.

6. A telephone exchange system comprising a telephone line, a link circuit, an operator's telephone set, a listening switch controlling the connection and disconnection of the operator's telephone set to and from the link circuit, and a source of signaling current connected with the telephone line through a normally closed contact of the listening switch when the link circuit is connected with the telephone line. 60

7. A telephone exchange system comprising a telephone line, a link circuit, an operator's telephone set, a listening switch controlling the connection and disconnection of the operator's telephone set to and from the link circuit, a source of signaling current whose connection with the telephone line is controlled by the listening switch, a relay 70 responsive to the connection of the link circuit with the telephone line, and circuit connections established upon the response of the relay when the listening switch is in its normal position over which current from the source of signaling current is connected 75 with the telephone line.

In witness whereof, I hereunto subscribe my name this 28th day of December A. D., 1917.

HENRY P. CLAUSEN.
